CAN-SEAMING MACHINE.

1,293,694.

Specification of Letters Patent. Patented Feb. 11, 1919.

Application filed March 13, 1917. Serial No. 154,583.

To all whom it may concern:

Be it known that we, FRANK W. BURPEE, JOHN H. BURPEE, and CLARENCE B. BURPEE, citizens of the Dominion of Canada, residing at South Bellingham, in the county of Whatcom and State of Washington, have invented certain new and useful Improvements in Can-Seaming Machines, of which the following is a specification.

10 This invention relates to a hand-operated can seamer of that class exemplified in an application filed by Frank W. Burpee on the 17th June, 1916 under Serial No. 104,272, and at present under examination by the

15 Office.
In the machine, which is the subject of this application, improvements are introduced in the structure of the frame and the operable mechanism of the machine to simplify and render the earlier machine referred to more satisfactory in working, and to permit adjustment of the machine to seam different sizes of cans.

20 To these features of improvement attention is drawn in the following specification, reference being made to the drawings by which it is accompanied, in which:

Figure 1 is a front elevation.

Fig. 2, a section to an enlarged scale of 30 the bottom can support showing the can body in position on it.

Fig. 3 is a cross section of the base of the frame on the line 3—3 in Fig. 1.

Fig. 4 is a plan of the end of the seaming 35 roller lever and its bushing on the pivot pin, and

Fig. 5 is a vertical section substantially on the line 5—5 of Fig. 1.

In these drawings 2 represents the base of 40 an open frame of the machine comprising a base member, two supporting columns and a top cross member, which latter carries the driving head of the seamer and its rotating mechanism. This frame 2 is secured to a 45 table or bench by a screw clamp 3 projecting downward from the middle of the base, and to enable the clamp to afford a more secure hold of the bench against oscillation about the clamp screw lugs 4 downwardly project 50 from the front of the base at each end, which lugs are designed to engage the edge of the table or bench to which the machine is secured.

55 Rotatably mounted on the upper end of a pin 5 secured in and upwardly projecting

from the middle portion of the base of the frame 2 is the hub of a flexible resilient disk 6, the diameter of which conforms to the inside diameter of the recessed bottom of the can to be seamed, so as to afford support to 60 that can against lateral displacement, and on the same stud 5 between the hub of the flexible plate and the base of the frame in which the pin 5 is secured, is mounted a handle lever 8 by which the disk 6 may be raised or 65 lowered, the underside of the boss of the handle lever having inclined faces 9 to engage a corresponding angled face on the boss 7 of the pin.

Rotatably mounted on a pin 11 secured in 70 and downwardly projecting from the upper cross member of the frame 2, and in alignment with the upwardly projecting pin 5 of the base, is the can driving head 12. This driving head is of a diameter to fit within 75 the can cover and its edge is knurled to effect a driving hold of it when the latter is pressed upward into engagement with it. The upper side of the driving head 12 is formed with bevel teeth 14 in which mesh 80 those of a pinion 16 formed on the hub of the crank handle 17 which is rotatably mounted on a stud 18 integral with the frame 2.

With this provision, if a can 15 with its 85 cover applied, is placed on the plate 6 and the handle 8 is partially rotated, the can will be lifted by the action of the inclines 9 to press the edge of the cover recess tightly upon the engaging edge of the driving head 90 12, and while that upward pressure is a yielding one owing to the flexible resilience of the plate 6, the can is strongly supported against lateral pressure to move it out of its axial alignment, by virtue of the edge of 95 the presser plate fitting the recessed bottom of the can. The can so clamped will rotate with the driving head 12.

The seaming rollers 22, 23, by which the closing of the cover seam to the body of the 100 can is effected, are mounted in a handle lever 21, which lever is mounted on a pin 20 between the upper end of one of the columns of the frame 2 and the corresponding end of the upper cross member of the same. To 105 provide a ready means of adjustment of this lever to seam different diameters of cans the lever is not mounted directly on the pin 20 but on an eccentric bushing 13 fitting the pin. This bushing has key projections 14 110

across its upper end, which key projections fit in a keyway across the face of the end of the cross member of the frame 2 which carries the upper end of the pin 20. The key 5 projections 14 are across the center of the pin, so that the bushing may be turned on the pin 20 to throw the eccentricity of the bushing to or from the center of the driving head and thereby lessen or increase the distance of the fulcrum bearing of the lever 10 from the center of rotation of the driving head and therefore of the can in the machine.

One of the seaming rollers is mounted on 15 each side of the middle line of the handle lever and stops are provided which limit the movement of each seaming roller at or adjacent the line joining the fulcrum bearing of the lever and the center of the driving head.

In operating on can bodies having a longitudinal seam, the end of which must of necessity be included in the seam of the cover to the can, difficulty is experienced in 25 rotating the multiplied thickness of this seam under the seaming rollers, if the fulcrum of the seaming roller lever is too rigidly connected to the can supporting means.

A sufficient measure of resilience is imparted to the fulcrum pin supports by providing a U bend 10 in the upper cross member of the frame 2 between the driving head and the fulcrum pin. The length of the side column of the frame which supports 35 the lower end of the fulcrum pin, affords sufficient resilience to the support of the lower end of the pin 20.

The improvements have all been suggested from practical experience in the 40 working of the device, and though comparatively trifling as structural changes, are all very material to the satisfactory working value of the machine. Without the downwardly projecting lugs on the base of 45 the frame the machine is liable to work loose under the opposite strains imposed on it in the use of the crank handle. And although the pressure of the seaming rollers is applied directly over the support afforded 50 the cover seam by the driving head, there is a slight tendency to lateral displacement of the can body on the plane surface of the original supporting plate 6, which tendency is completely met by fitting that plate into 55 the recess of the can bottom as described.

Again, the direct connection between the seaming roller fulcrum pin and the driving head imposes a severe strain on the rotating gear to move the longitudinal seam of the can body past the seaming rollers, which the 60 resilience in the form of the column, and the U bend in the upper member of the frame materially lessens, without impairing the satisfactory closure of the seam. And the eccentric bushing providing for variation 65 in the distance of the axis of the pivot of the seaming roller lever from the axis of rotation of the driving head provides a simple means enabling the same seaming roller lever to serve for different sizes of cans, while such 70 other parts as the supporting plate 6 may be furnished for each size of can the machine may be required to seam.

Having now particularly described our invention, we hereby declare that what we 75 claim as new and desire to be protected in by Letters Patent, is:

1. In a can cover seamer having a can driving head rotatably mounted within a suitable frame and a seaming roller lever 80 pivotally mounted to said frame adjacent the driving head, means for varying the distance between the center of the driving head and the pivotal axis of the lever, said means comprising a pin secured in the frame, an 85 eccentric bushing the bore of which fits the pin and on the outside of which the seaming roller lever is mounted, a key projection extending across the center of the bore at right angles to the line joining the center of 90 the inside and outside circles of the bushing, and keyways in the face of the frame adjacent the pin to receive the key projections of the bushing.

2. In a can cover seamer wherein the can driving head is rotatable within a suitable frame, and the seaming rollers are mounted in a lever which is pivotally mounted adjacent the driving head, means for imparting resilience to that portion of the frame between the driving head and the pivot of the lever, said means comprising a U bend in the frame intermediate of the driving head and the lever pivot.

In testimony whereof we affix our signatures.

FRANK W. BURPEE.
JOHN H. BURPEE.
CLARENCE B. BURPEE.
